FAN

Peter P. Grad, Woodstock, N.Y., assignor to Rotron Manufacturing Company, Inc., Woodstock, N.Y., a corporation of New York

Filed Feb. 3, 1965, Ser. No. 83,678

Term of patent 14 years

(Cl. D62—4)

FIG. 1

FIG. 2

FIGURE 1 is a perspective view of the fan showing my new design; and

FIGURE 2 is an elevation view of the fan showing my new design.

The dominant features of the design reside in the portions shown in full lines.

I claim:

The ornamental design for a fan, substantially as shown and described.
